US0D1073411S

(12) **United States Design Patent** (10) **Patent No.:** **US D1,073,411 S**
(45) **Date of Patent:** **** May 6, 2025**

(54) **CONTAINER**

(71) Applicant: **Igloo Products Corp.**, Katy, TX (US)

(72) Inventors: **James Duke**, Katy, TX (US); **John Maldonado**, Katy, TX (US); **James McKenrick**, Katy, TX (US)

(73) Assignee: **Igloo Products Corp.**, Katy, TX (US)

(**) Term: **15 Years**

(21) Appl. No.: **29/872,157**

(22) Filed: **Mar. 7, 2023**

(51) **LOC (15) Cl. 07-01**

(52) **U.S. Cl.**

USPC **D7/510; D7/511; D7/608**

(58) **Field of Classification Search**

USPC D3/202, 229; D7/323, 368, 387, 402, D7/409, 507, 509-511, 523, 589, D7/601-603, 608, 619.1, 619.2, 620, 621, D7/624.1, 624.2, 624.3; D9/455, 500, D9/529

(57) **CLAIM**

The ornamental design for a container as shown and described.

DESCRIPTION

FIG. 1 is an upper perspective view of a container, showing our new design;

FIG. 2 is a lower perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

The broken lines shown in the drawings are included for the purpose of illustrating the unclaimed boundary or unclaimed portions of a container. The broken lines form no part of the claimed design.

1 Claim, 8 Drawing Sheets
